United States Patent Office.

JOHN L. AGNEW AND CHARLES E. WRIGHT, OF NEGAUNEE,
MICHIGAN.

Letters Patent No. 87,750, dated March 16, 1869; antedated February 27, 1869.

IMPROVEMENT IN CHILLED PLATES FOR ORE-CRUSHERS.

The Schedule referred to in these Letters Patent and making part of the same.

To all whom it may concern:

Be it known that we, JOHN L. AGNEW and CHARLES E. WRIGHT, of Negaunee, in the county of Marquette, and State of Michigan, have invented new and useful Improvements on the Chilled Plates and Surfaces between which Minerals are Crushed, Broken, or Ground; and we do hereby declare that the following is a full and exact description thereof, reference being had to the accompanying drawings, making a part of this specification, in which—

Figure 2 is a plan of the chilled plates used by the Blake crusher, containing our improvements.

Figure 1 is a vertical section of the same through the line 'X L'.

By reference to the figs. 1 and 2, let O O represent the bars of soft iron, cast in the chilled plates or surfaces.

S S are the points of contact with the minerals.

While the points or ribs S S are wearing away, the soft-metal bars O O wear also, and, in consequence thereof, the points or ribs S S remain constantly sharp

or prominent, until the bars O O are completely worn away.

Fig. 1 represents, by a vertical section, the ribs, or points S S cast on each side of the chilled plate. The reason for this is, that when the points, or ribs S S are worn off on the working-face, it may then be reversed, bringing the uninjured face or side to the front, and thereby causing the chilled plates to last nearly twice as long.

The action of crushing or grinding minerals tends to destroy the ribbed or uneven surface, by making it smooth, thereby impairing the efficiency of the machine.

What we claim as our invention, and desire to secure by Letters Patent, is—

The plate for ore-crushers, constructed of wrought and chilled iron, in the manner described and for the purpose set forth.

JOHN L. AGNEW.
